UNITED STATES PATENT OFFICE.

ROLLAND S. TROTT, OF DENVER, COLORADO.

CANTALIVER-SPRING MOUNTING.

1,245,748.

Specification of Letters Patent. Patented Nov. 27, 1917.

Application filed March 31, 1915. Serial No. 18,846.

To all whom it may concern:

Be it known that I, ROLLAND S. TROTT, a citizen of the United States, residing at the city and county of Denver and State of Colorado, have invented certain new and useful Improvements in Cantaliver-Spring Mountings, of which the following is a specification.

My invention relates to an improvement in cantaliver spring mountings, and the object is to provide a mounting for cantaliver springs that will permit horizontal movement of the axle to which the spring is connected without giving the axle a vertical movement as part of the horizontal action; and further to provide means for a resilient drive through the cantaliver spring; and still further to provide means to maintain the axle at right-angles to the line of draft. With these objects in view, my invention comprises a cantaliver spring supported at one point upon an axle and having connection with the frame of the vehicle at two other points in such a manner that the axle end of the spring may be made to move in a nearly horizontal path as the springs are swung back or forward with respect to the frame; and it further consists in details of construction which will be hereinafter described and pointed out in the claims.

In the accompanying drawings:

Figure 1 is a fragmentary view of the rear end of the frame showing the rear axle cantaliver mounting;

Fig. 2 is a transverse vertical section on line 2—2 of Fig. 1;

Fig. 3 is a similar sectional view on the line 3—3 of Fig. 1;

Fig. 4 shows a slight variation in the mounting in which the location of the links and cross-shaft is reversed;

Fig. 5 is a view corresponding to Fig. 1, except that the links extend down from the frame instead of up;

Fig. 6 is a similar view but corresponding with the construction shown in Fig. 4; and

Figs. 7 and 8 show rollers in lieu of arms or links for the connection between the frame and cantaliver springs.

A, indicates the frame, and 1 is the rear axle, while 2 indicates the cantaliver spring supported at the rear end upon the rear axle, and having its forward end connected to the frame by a link 3, while at an intermediate point (but preferably off center) the spring is pivotally connected at 4 to the upper ends

of the arms 5, 5, which latter are secured rigidly upon the cross-shaft 6, which is mounted to turn in the frame A, and extends to the other side where the parts are duplicated, the cross-shaft being the means illustrated for keeping the axle square.

The arms 5 are of greater length than the links 3. By proper proportioning of these arms and links, the tilt of the springs, their camber, and the position of the middle pivot, the axle end of the spring may be made to move in a nearly horizontal path as the springs are swung back or forward on their links and arms.

In the construction shown in Fig. 4, the same general proportions are maintained, but the relation of parts is reversed, that is to say the cross-shaft 6' for keeping the axle square is at the end, and has secured thereto short arms 3' in this instance, instead of the links 3 of the former construction. In this form, the longer links 5' are pivotally connected with the cantaliver spring at their upper ends as at 4', at an intermediate point, and pivotally connected to the frame A at their lower ends.

Figs. 5 and 6 correspond with the construction just described, except in this instance the arms 5^a secured to the cross-shaft 6^a extend downwardly to the springs 2, thus providing for a frame which is mounted high above the axle, the links 3^a extending in a corresponding direction from the frame to which they are pivoted. The only difference between the constructions shown in Figs. 5 and 6 is that in Fig. 6 the cross-shaft 6^b is connected through arms 3^b to the end of the spring, and instead of the longer arms 5^a, links of corresponding length are pivotally connected with the frame and extend downwardly therefrom where they are pivotally connected with the spring at a point at or preferably somewhat away from center, as at 8.

Figs. 7 and 8 illustrate the same principle, in which in lieu of the arms or links extending from the frame to an intermediate part of the spring, rollers 9, 9, are connected to the frame and embrace the opposite sides of the spring, Fig. 7 showing a low mounted frame, and Fig. 8 a high frame. In Fig. 7, the upper surface of the spring with which the roller comes in contact is convex as at 10; and in Fig. 8, it is concaved as 11, the rollers in both instances embracing the opposite parallel surfaces. The

55 a path parallel to the frame, means attached to the frame to maintain the axle square with the line of draft, and means to resiliently oppose said movement of the axle.

2. The combination with a vehicle frame,

ROLLAND S. TROTT.
